UNITED STATES PATENT OFFICE.

DELIZIO BREVETTI, OF NEW YORK, N. Y.

JEWEL-SETTING.

1,099,634.

Specification of Letters Patent.

Patented June 9, 1914.

Application filed September 16, 1912. Serial No. 720,477.

To all whom it may concern:

Be it known that I, DELIZIO BREVETTI, a subject of the King of Italy, residing in the borough of Manhattan, city, county, and State of New York, have invented certain new and useful Improvements in Jewel-Settings, of which the following is a specification, reference being had to the accompanying drawings.

10 This invention relates to improvements in jewel settings; and an object of this invention is to provide a jewel setting which will be simple in construction, comparatively cheap in manufacture and efficient, durable 15 and reliable in operation and use.

Another object of this invention is to provide a jewel setting which will require a minimum of labor in setting and securing the stones in place.

20 Another object of this invention is to provide a jewel setting of which the stone-retaining prongs will be so hidden as to be practically invisible and which will, therefore, have a greatly improved appearance 25 over the settings now on the market.

A further object of this invention is to provide a jewel setting the parts of which will not become entangled with the clothing of the wearer of the setting.

30 In the drawings illustrating the principle of this invention and the best mode now known to me of applying that principle, Figure 1 is a plan view of a fragment of my new setting; Fig. 2 is a section on the line A—A of Fig. 1; Fig. 3 is a section on the line B—B of Fig. 1; Fig. 4 is a perspective view, partly in section, of a fragment of my new setting; Fig. 5 is a fragmentary perspective view of my new setting, showing 40 the stones in place; Fig. 6 is a fragmentary view of a modified form of setting in which my invention is embodied and in which some of the stones are shown in place; Fig. 7 is a plan view of another modified form of setting embodying my invention, some of the stones being shown in place; and Fig. 8 is a view similar to Fig. 4 and shows still another modified form of this invention.

50 My new setting is preferably stamped by means of suitable dies from strips of sheet metal *a*. By means of these dies there are formed the cup-shaped seats *b*; and from the parts *c* lying between these cup-shaped seats *b* there are struck up by the dies at 55 the time of the formation of the latter the prongs or claws *d*. These prongs or claws

d are so arranged that when they are pressed down into place, each prong or claw engages two stones *e* lying side by side between the ends of the setting; and the seats *b* for the stones *e* are located so closely together that the stones within them lie so closely adjacent that each prong *d* is enabled to engage two stones as shown in Fig. 5. It is to be observed that the openings *f* left by the 60 striking up of the claws lie wholly between the seat of the stones and that the metal *g* lying outside of these seats is not marred or mutilated by openings and is left entirely available for ornamentation, thereby insuring a setting of good appearance. The openings *f* serve to lessen the stiffness of the strip *a* of sheet-metal, which may be readily bent into the desired shape. Moreover, these openings *f* serve as vents for the wash-water used in cleaning the stones. 65

In Fig. 6 there is shown part of a setting in the form of a cornered (or polygonal) piece, the sides *h*, *i*, meeting at a corner *j*. The stone *k* at the corner is preferably held 70 also by means of claws or prongs *d'* struck up from the metal in the corner. In this case no cup-shaped seats *b* for the stones are provided but the prongs are struck up from the metal of the strip and the stones *e* 75 between the corners are placed so close together that the claws or prongs lying between the stones are enabled to engage two stones. Moreover, as shown in this figure, the prongs or claws *d''* need not be pointed 80 but may be rounded. 85

In Fig. 7 there is shown a substantially oval-shaped setting in which no seats are formed for the stones, which are placed so close together that the intermediate claws 90 or prongs *d* engage two of the closely adjacent stones *e* which lie between the end-stones *m*. These end stones may be held by means of a single prong *d''* or by means of two prongs *d''*, as may be found most desirable, the end-prongs *d''*, being struck up from the material of the strip. 95

When the stones are put into position, and the prongs *d* are bent down into retaining position it will be found that the prongs are 100 so hidden as to be practicably invisible and the appearance of the setting is greatly improved by this substantial invisibility of the prongs *d*. Again, the appearance of the setting is improved by the fact that the 105 prongs cover the openings *f* formed by their being struck up from the metal, since the 110

metal from which the prongs *d* are struck up lies wholly between the seats of the stones and the openings *f* do not extend out into the metal *g* beyond the seats *b*. Therefore, this metal *g* beyond the seats *b* may be used for purposes of ornamentation, the appearance of which will not be detracted from by reason of openings therein which would mutilate or mar the setting. Since each pair of prongs *d* engage a pair of stones *e*, it will be seen that the labor of setting the stones *e* will be greatly reduced; and, moreover, the initial cost of the dies will also be less than in the case in which each stone is held by four prongs which engage only that stone and no other, as is the common practice today in the setting of jewels, when a series of stones are set side by side.

In Fig. 8 there is shown a setting in which the inner or lower face of the prongs or claws *d''* is concaved or dished so that the prongs *d''* are convexed upwardly and have a rounded appearance and give to the setting an appearance of ornamentation. These prongs *d''* are also rounded at their inner ends and they are struck up in part from the upper portions of the walls of the cup-shaped seats *b''*, as will be apparent from an inspection of Fig. 8 and particularly with reference to the holes *f'* which are left by striking up these prongs *d''*. This taking of some of the metal from the walls of the cup-shaped seats *b''* permits the base portions of the prongs *d''* to be set in closer together and nearer the part *c* lying between them. However, the seats may be on flat metal, as is shown at *b'* in Fig. 6 and at *b''* at Fig. 7, where the stones are shown omitted for the purpose of giving a clear view of the seats *b'*, *b''*.

I claim:

1. A jewel-setting comprising a sheet having a pair of seats for the stones, said sheet extending a substantial distance outwardly from the seats; and a prong struck up from the material between the seats and bent to a position substantially in the plane of the sheet; said prong lying substantially entirely between the seats and being arranged to engage simultaneously both the stones mounted therein and to conceal the opening made in the sheet by the prong's being struck up therefrom.

2. A jewel setting comprising a sheet having a pair of seats for the stones, said sheet extending a substantial distance outwardly from the seats; and a pair of reversely-disposed prongs which are struck up from the material between the seats and bent to a position substantially in the plane of the sheet; said prongs lying substantially entirely between the seats and being arranged to engage simultaneously both the stones mount-

ed therein and to conceal the openings made in the sheet by the prong's being struck up 65 therefrom.

3. A jewel-setting comprising a sheet having a pair of cuplike seats for the stones, said sheet extending a substantial distance outwardly from the seats; and a prong 70 struck up from the material between the seats and bent to a position substantially in the plane of the sheet; said prong lying substantially entirely between the seats and being arranged to engage simultaneously 75 both the stones mounted therein and to conceal the opening made in the sheet by the prong's being struck up therefrom.

4. A jewel setting comprising a sheet having a pair of cuplike seats for the stones, 80 said sheet extending a substantial distance outwardly from the seats; and a pair of reversely-disposed prongs which are struck up from the material between the seats and bent to a position substantially in the plane 85 of the sheet; said prongs lying substantially entirely between the seats and being arranged to engage simultaneously both the stones mounted therein and to conceal the openings made in the sheet by the prongs' 90 being struck up therefrom.

5. A jewel setting comprising a sheet having a pair of cuplike seats for the stones, said sheet extending a substantial distance outwardly from the seats; and a prong 95 struck up in part from the material between the seats and in part from the upper portions of the walls thereof and bent to a position substantially in the plane of the sheet; said prong lying substantially entirely between 100 the seats and being arranged to engage simultaneously both the stones mounted therein and to conceal the opening made in the sheet by the prong's being struck up therefrom.

6. A jewel setting comprising a sheet having a pair of cuplike seats for the stones, said sheet extending a substantial distance outwardly from the seats; and a dished 105 prong struck up in part from the material between the seats and in part from the upper 110 portions of the walls thereof and bent to a position substantially in the plane of the sheet; said prong lying substantially entirely between 115 the seats and being arranged to engage simultaneously both the stones mounted therein and to conceal the opening made in the sheet by the prong's being struck up therefrom.

Signed at the borough of Manhattan, city, county and State of New York, this fourteenth day of September, A. D., 1912, in the presence of the two undersigned witnesses.

DELIZIO BREVETTI.
